UNITED STATES PATENT OFFICE.

BENJAMIN CARLEY AND WILLIAM W. EVANS, OF PATERSON, NEW JERSEY.

EXHAUST-VALVE FOR STEAM-ENGINES.

SPECIFICATION forming part of Letters Patent No. 247,241, dated September 20, 1881.

Application filed December 30, 1880. (No model.)

To all whom it may concern:

Be it known that we, BENJAMIN CARLEY and WILLIAM W. EVANS, both of Paterson, in the county of Passaic and State of New Jersey, have invented certain new and useful Improvements in Exhaust Valves and Ports for Steam-Engines, of which the following is a specification.

Though our invention is applicable to steam-engines generally, it is specially intended for locomotive-engines, and the object is to provide for a free exhaust throughout the stroke while working steam expansively.

The invention consists in a novel combination, in an engine, of an independent exhaust-valve, an auxiliary cylinder and piston or pistons for actuating said valve, a steam-chest separate from said auxiliary cylinder, and a valve-seat having in it main steam-ports and auxiliary steam-ports for admitting steam to act upon said piston or pistons, and a main valve controlling both said main steam-ports and said auxiliary steam-ports, whereby provision is afforded for opening wide the exhaust-valve at the beginning of the stroke of the engine-piston and leaving it wide open during the whole or the greater part of the stroke.

In the accompanying drawings, Figure 1 represents a plan view of a locomotive-cylinder and main steam-valve and a section through an auxiliary cylinder in which are the exhaust-valve and its actuating-pistons. Fig. 2 represents a transverse section upon the dotted line *x x*, Fig. 1; and Fig. 3 represents a plan and horizontal section upon the dotted line *y y*, Fig. 2, the main steam-valve being removed.

Similar letters of reference designate corresponding parts in all the figures.

A designates a locomotive-engine cylinder, having a valve-seat, *A'*, upon its upper surface, and constructed with two main steam-ports, *a a*, leading from near the middle of the cylinder to each end thereof.

B designates the steam or valve chest, and *C* designates a slide-valve working upon the seat *A'* to control the passage of steam through the main steam-ports. This usual exhaust-port between the two steam-ports *a a* is not employed, and hence the valve *C* need have no

exhaust-cavity or *D*, but consists simply of a flat-faced piece of metal actuated in the usual way by a strap or yoke or other suitable means. Steam is supplied to the steam or valve chest *B* in the usual way by an inlet-passage, *B'*, from the boiler.

D designates a small auxiliary cylinder parallel with the main cylinder *A*, and communicating with the two ports *a a* by means of passages or ports *b b*, and in said cylinder *D*, opposite or ranging with said passages or ports *b b*, are other ports, *c c*, which communicate with the exhaust chest or chamber *E*.

The exhaust-valve *F*, in this example of our invention, consists of two piston-heads, each controlling one of the ports *b* and its opposite port *c*; but the exhaust-valve might consist of a slide-valve, the ports being suitably arranged. The exhaust-valve *F* is actuated by pistons *G*, working in opposite ends of the auxiliary cylinder *D*, and the pistons and valve are all connected by a common rod, *H*, fitting in guides formed in the heads *D'* of the auxiliary cylinder *D*, so that the valve and its actuating-pistons all move in unison.

Upon the rod *H*, between the pistons *G* and the adjacent heads *D'*, are springs *I*, which cushion the pistons *G* and prevent shock as they are impelled in either direction by the action of the steam.

Steam is admitted to act upon the pistons *G* by means of passages *d d*, extending from each end of the auxiliary cylinder, and terminating in auxiliary steam-ports *e e* in the valve-seat *A'*, at one side of and in proximity to the main steam-ports *a a*.

The main steam-valve *C* has at one end an extension, *C'*, of greater length than the valve, and which covers the ports *e e*, as clearly shown in Fig. 1. In the extension *C'* of the valve *C* is a port, *f*, which by the movement of the valve is brought opposite the ports *e e* alternately, and admits steam first to one end and then to the other end of the cylinder *D*, to act alternately upon the pistons *G* and reciprocate the exhaust-valve *F*. After being admitted to the auxiliary cylinder *D* to act upon one piston *G*, it is necessary that the steam should be exhausted to enable the valve to be moved

freely when the steam acts upon the other piston, and this is effected by providing exhaust-notches *s* in the cylinder *D*, through which steam is exhausted into the exhaust-chamber *E*.

It is desirable that the exhaust-valve *F* should have a slight lead over the main valve *C*, so that a free exhaust will be afforded the moment the main piston commences its stroke. To effect this the ports *e e* are made a little nearer together than are the ports *a a*, as seen clearly in Fig. 3, and by reference to Fig. 1 it will be seen that the one of the ports *e* which is partly open through the valve-port *f* is open to a greater extent than the opposite port *a*, which is also partly open. In Fig. 1 the exhaust-valve *F* is represented as having already been moved toward the bottom of the drawings, opening communication between one pair of ports *b c* and cutting off communication between the ports of the other pair by one of the piston-heads *F* covering both ports. The exhaust-valve *F* is thus thrown wide open just before the main piston commences its stroke, and remains wide open during the whole stroke, whether the engine is working expansively or not; and it will be seen that the main valve may be set to get any degree of expansion without interfering with the exhaust, because after being once moved to open the exhaust from one end of the cylinder the exhaust-valve remains stationary until it is moved to open the exhaust from the opposite end of the cylinder.

Although we have shown two pistons *G*, upon which steam acts alternately, a single piston acted upon by the steam alternately on

opposite sides might be substituted for the two pistons.

We are aware that it is old to combine with the main cylinder of an engine an auxiliary cylinder containing piston or puppet valves, which control both the admission of steam to and its exhaust from the main cylinder, and which are all fixed upon a common valve rod or stem, and hence we do not claim such construction as of our invention.

What we claim as our invention, and desire to secure by Letters Patent, is—

1. The combination, in a steam-engine, of an independent exhaust-valve, an auxiliary cylinder, and a piston or pistons for working said valve, a steam-chest separate from said auxiliary cylinder and containing a valve-seat having in it main steam-ports and auxiliary steam-ports for admitting steam to act upon said piston or pistons, and a main slide-valve controlling both said main and auxiliary steam-ports, and serving to admit steam both to the main cylinder of the engine and to the auxiliary cylinder to act upon said piston or pistons, substantially as specified.

2. The combination of the main cylinder *A* and auxiliary cylinder *D*, provided with ports *a a*, *e e*, and *b b* and *c c*, the slide-valve *C*, containing the port *f*, and the exhaust-valve *F* and pistons *G*, all substantially as specified.

BENJAMIN CARLEY.
WILLIAM W. EVANS.
